UNITED STATES PATENT OFFICE.

BRUNO THOMAS, OF SEATTLE, WASHINGTON.

ELECTRIC FURNACE FOR TREATING GASES.

1,367,842.

Specification of Letters Patent.

Patented Feb. 8, 1921.

Application filed April 30, 1917, Serial No. 165,563.

To all whom it may concern:

Be it known that I, BRUNO THOMAS, a citizen of the United States, and resident of the city of Seattle, county of King, and 5 State of Washington, have invented certain new and useful Improvements in Electric Furnaces for Treating Gases, of which the following is a specification.

My invention relates to electrical furnaces wherein the transformation of gases is produced by the action of an electrical arc thereon, of which the more generally known application is for the purpose of the oxidation or fixation of atmospheric nitrogen.

The object of my invention is to improve the apparatus and methods employed to thereby decrease the cost of production of a unit of the product.

20 My present invention comprises certain improvements in the construction of the apparatus which improvements will be hereinafter described and then particularly pointed out in the claims.

25 In the accompanying drawings I have shown my invention in the form of construction which is now most preferred by me.

Figure 1 is a vertical section through a 30 furnace having the simplest construction. Fig. 2 is a like section through a furnace using horn electrodes.

Fig. 3 is a vertical section through a furnace having air supply mechanism which 35 introduces a portion of the air at the center but having a whirling movement which throws it outward through the arc.

Fig. 4 is like Fig. 3 except that all the air is introduced at the center and is given 40 a cyclonic movement before introduction.

Fig. 5 is similar to Fig. 4 but with the use of horn electrodes which are spaced about the air inlet.

Fig. 6 is a plan view of the construction 45 shown in Fig. 5.

Fig. 7 is like Fig. 5 except that the horn electrodes are twisted in the form of conical helices or spirals.

Fig. 8 is a vertical section and Fig. 9 a 50 plan, partly in broken section, showing one preferred type of furnace construction.

In the more common types of furnaces as hitherto employed for oxidation of gases under the influence of the electrical arc, it 55 has been customary to form a single electrical arc in, or adjacent to, the central axis

of the furnace and to supply the air, or gases, tangentially to the furnace to thereby form a whirling outer layer, this producing a less dense central core of air in 60 which the arc is maintained. In this type of furnace a long stable arc is formed. The action of the arc upon the air is most intimate and effective upon that part which has been forced from the outside inward, 65 or toward the central axis. In consequence, the oxidation effect of the electrical arc has been lower than it should be.

In my present invention I employ a plurality of electrical arc which are merged 70 together to form a composite arc of increased surface and form this composite arc in such shape and pass the air, or gases, through this arc in such manner, as secures a more effective oxidizing action of the arc 75 upon the air than is secured by the former methods and apparatus.

In the form of furnace shown in Fig. 2, I employ a series of electrodes, 2, in the form of horn electrodes, these being in 80 number corresponding with the number of phases in the current employed, and being grouped about a central point or axis. The air is supplied under a pressure which is more or less greater than that in the furnace chamber 1, entering through a passage 3 which discharges from between the electrodes. The reduction of pressure on entering the furnace, causes a lateral expansion, this being assisted by the expanding mouth 85 11, when such a mouth is used. In consequence, the air is brought into intimate contact with the arc.

In the furnace shown in Fig. 2, arcs are formed joining the electrodes 2 and may 95 also be formed between these electrodes and a common return electrode, if such be employed. In the furnace shown in Fig. 1, a single phase current is used, the arc extending from the air inlet pipe 31, which 100 forms one electrode, to the pipe 10, which forms the other electrode.

In the furnace, as shown in Fig. 3, the electrode 20 has the air inlet 3 therein and also a dome-shaped circular chamber 21 into which the air is supplied from a passage 22, which discharges tangentially of the chamber 21, thereby producing a whirling movement in the air. As the air is forced to the center in order to escape 110 through the discharge nozzle 3, the rate of whirling is intensified and it is discharged

into the furnace whirling at a high rate. As it escapes from the nozzle 3 it is freed from restraint and, due to the centrifugal tendency produced by this whirling action, 5 tends very strongly to spread radially, or from the central axis of the furnace toward its outer wall. In doing this it must pass through the arcs which extend between the electrodes.

10 In addition to the above features, Fig. 3 shows a supplemental air supply entering the furnace through the annular opening 12 existing between the electrode 20 and the wall of the furnace. This permits the 15 supply of an additional volume of air which is caused to impinge directly upon the arcs which have been expanded by the action of the air entering through the nozzle 3.

The furnace shown in Fig. 4 is the same 20 in construction and action as that of Fig. 3, except for the omission of the annular air inlet 12.

The furnace shown in Fig. 5 differs from that shown in Fig. 4, only in having a 25 sharper angled conical mouth 11 and in using horn electrodes 2, to which a multiphase current is applied. It is also like that of Fig. 2 except for the use of the preliminary chamber 21 in which the whirling effect 30 is given the air. Fig. 6 shows a plan view of the furnace shown in Fig. 5. The furnace of Fig. 7 is like that of Figs. 5 and 6 with the horn electrodes 23 curved into conical helices.

35 In the furnace shown in Figs. 8 and 9, the preliminary air chamber 21 is used to give the air a whirling movement before its introduction to the furnace chamber. The electrodes consist of tubular members 24 40 which lie flat upon the conical bottom of the chamber. These are kept cool by circulating water therein.

In this furnace, the length of the furnace 45 relative to its diameter is small. I have also shown a common return electrode 4, this being hollow and water cooled. It is of less diameter than the furnace and centrally placed; thus leaving an annular discharge opening. The arc fills this furnace 50 chamber. The air passes through the arc and is then immediately discharged into cooling passages, thus much facilitating cooling of the combined gases before sufficient time has elapsed to permit dissociation 55 tendencies to have any material effect.

It is well known that combination of the 60 gases under the action of the electric arc takes place with greater rapidity at high temperatures than at lower. It is also well known that dissociation of the gases also acts more rapidly at high temperatures.

In the ordinary furnace using long arcs,

the time of exposure to the high temperatures of the arc, during the passage through the furnace, is so much greater than the time necessary for dissociation to take place, that only a small part of the latter part of this period is materially effective in producing any lasting result. This is one cause of inefficiency.

With the purpose of remedying this fault I have made the furnace short, as is shown in Fig. 8, and of a construction which promptly discharges the gases into cooling passages, thereby securing effective cooling 75 before the tendency for dissociation can act very fully.

What I claim as my invention is:

1. A furnace for electrically combining gases having an arc forming chamber, a preliminary receiving compartment for the gases into which the gases are introduced tangentially to thereby produce a whirling movement therein, an air conduit connecting said two chambers and positioned 80 axially of each, and electrodes within the arc forming chamber and grouped about the said air inlet conduit.

2. In a furnace for electrically combining gases, an arc-forming chamber having a central air inlet, a plurality of electrodes forming terminals of a multiphase current and grouped about said air inlet, means for giving the air a whirling movement before entering said air inlet, said means comprising a preliminary receiving chamber connecting centrally with and discharging through said air inlet, and means for introducing air tangentially into said preliminary receiving chamber.

3. A furnace for electrically combining gases having an arc forming chamber, a preliminary receiving compartment for the gases into which the gases are introduced in a manner to produce a cyclonic whirling movement therein, an air conduit connecting said two chambers and electrodes within the arc forming chamber and grouped about the said air inlet conduit.

4. An electric furnace of the type named 110 having a centrally placed air inlet at one end and an annular air discharge opening at the other end, a plurality of electrodes entering through said air inlet, extending outwardly as a loop and returning to and 115 passing out through said air inlet, and an electrode complementary to the first named electrodes, placed within the annular exit opening at the other end of the arcing chamber.

Signed at Seattle, Washington, this 25th day of April, 1917.

BRUNO THOMAS.
